UNITED STATES PATENT OFFICE

EDWIN B. GOODWIN, OF BOULDER, COLORADO.

SEPARATOR AND CLASSIFIER FOR PLACER MATERIAL, GROUND ORE, AND THE LIKE.

1,122,908.

Specification of Letters Patent. Patented Dec. 29, 1914.

Application filed April 22, 1914. Serial No. 833,783.

To all whom it may concern:

Be it known that I, EDWIN B. GOODWIN, a citizen of the United States, residing at Boulder, in the county of Boulder and State 5 of Colorado, have invented certain new and useful Improvements in Separators and Classifiers for Placer Material, Ground Ore, and the like; and I do hereby declare the following to be a full, clear, and exact description of the invention, such as will enable others skilled in the art to which it appertains to make and use the same.

This invention relates to separating devices for placer material, ground ore and the 15 like and particularly to those devices of the class described in which the separation is accomplished largely by gravitation, and has for an object to provide, in such a device, improved means for agitating the material being worked.

Another object is to provide improved 25 means for holding the heavier materials, after separation, from thereafter moving to the point of discharge of the lighter material and there again mixing and discharging with the lighter materials.

With these and other objects in view the invention comprises certain novel construction, combination and arrangements of parts 30 as will be hereinafter more fully described and claimed and as shown in the accompanying drawings in which similar characters of reference indicate corresponding parts throughout the several views and in 35 which—

Figure I, is a side view of my separator and classifier the lower portion of the barrel being cut away to expose the inside parts to view. Fig. II, is an end elevation of my 40 separator and classifier with a quarter cut away as in Fig. I. Fig. III, is a view of the central shaft partly in section and partly in elevation or plan. Fig. IV, is an elevation view of a fragment of the shaft showing 45 plow arms and plow attached thereto and at position depending therefrom. Fig. V, is a view of the fragment and parts shown in Fig. IV, looking down upon the same from above the shaft. Fig. VI, is an end view of 50 the fragment and parts shown at Fig. IV.

In the matter of separation of minerals in a mass by gravitation the main idea is the removal of all impediments to the natural 55 tendency of the heavier particles to drop to the bottom of the mass. The pressure of adjacent particles of lighter material is the

primary impediment. Water is a material aid in making such a separation but, when used in ordinary manner, it forms in a stream flowing over the surface of the material being worked and carries with it much of the valuable mineral which consists of very fine particles—the water, as to these finer particles, thus overcoming the attraction of gravitation. This is the secondary impediment. To overcome these impediments and give the attraction of gravitation an opportunity to act freely and effectively upon all of the heavier material in the mass—whether in larger or smaller particles—is 60 my purpose in this invention. I accomplish this purpose by providing a conical barrel 1 mounted as by arms 2 and 3 upon a central shaft 4 which, in turn, is revolubly mounted in trunnioned bearings 5 and 6 mounted in supports 7 and 8 as at 9 and 10 to permit the raising or lowering of either bearing so as to give the desired slant or incline to the central shaft 4 and to the barrel 1.

On the inside of the barrel 1, and secured thereto in any ordinary manner as by rivets 12, I provide a spiral rifle 11 preferably inclined toward the smaller end of the barrel as clearly shown at Fig. I. It will be understood that the spiral may be single or multiple as desired, the principle and method of operation being the same in either case.

Between the turns of the rifle 11 I provide pins 13 preferably set in strips 14 attached in any ordinary manner to the barrel 1. In my drawing I show but three strips 14. To show more would unnecessarily complicate the drawing, but it will be understood that strips 14 with pins 13 may be placed at any desired intervals in the space 95 between the turns of the rifle 11.

The larger end of the barrel is partly closed by a ring 15 standing in a plane at right angles to its axis, and the inner edge of the ring has a flange 16 projecting into the barrel at right angles from the ring. Near the smaller end of the barrel I provide it with an internal flange 17 standing at right angles to its axis, and the inner edge of this flange is continued into a secondary flange 18 projecting obliquely from the flange 17 toward the smaller end of the barrel. As seen in Fig. II the inner diameter of the secondary flange is smaller than the small end 30 of the barrel.

In the portion 19 of the barrel 1 between the flange 17 and the smaller end of the

2

barrel, agitating points 20 are provided similar to pins 13 but preferably smaller. But one set is shown in the drawing. As many as desired may be used.

5 The shaft 4 is tubular and provided at one end with suitable connection as 21 for hose or other water supplying means. The opposite end is plugged as at 22 and the shaft is provided with holes 4^a for a distance substantially equal to the length of barrel 1, all as clearly shown at Fig. III, for emitting a spray of water within the barrel 1 when the shaft is in position shown in Fig. I, and is supplied with water 10 through connection 21. Plows 23 are also provided, at as frequent intervals as desired and generally following the space between the turns of the spiral riffle 11 (three only being shown in the drawing), carried 15 by arms 24 attached to shaft 4 as by clamps 20. It is desirable to set the plows at an angle as to shaft 4 as clearly shown at Figs. I. and V. and indicated at Figs. IV. and VI. and this is accomplished by twisting 25 the arms 24 between the clamps and the plows, so that the two arms carrying a single plow will diverge from each other as they project from the shaft. Thus, by causing the arms 24 to diverge more or less, 30 any desired angle or slant may be given to the plows. The plows are further adjustable in that their distance from the sides of the barrel 1 may be changed and fixed as desired by providing a plurality of holes 35 26 in the arms 24 so that the plows 23 may be bolted to the arms 24 at any desired height. Any suitable means as chute 27 may be provided for supplying the material to be worked. Any ordinary means may 40 be provided upon shaft 4 at any suitable point thereon as at 28 for connecting the same with power for revolving the shaft and barrel carried thereby.

In operation the material to be worked 45 is supplied through chute 27 to the inside of the barrel 1 while the same is being slowly revolved by means of the power applied to shaft 4 as above mentioned. At the same time water is supplied to shaft 50 4 as described and thus the inside of the barrel is subjected to a spray of water through the holes 4^a. Placer material or ground ore, being mobile, naturally follows the incline of the lower side of the barrel 55 1 and fills the lower portion of the barrel up to the point of overflow 29 at the inner edge of the ring 15 which is here shown as being coincident with the flange 16 though flange 16 may be positioned at any desired 60 height upon the ring 15. As the material passes from the point of supply at chute 27 to the overflow 29 the action of the water and the natural mobility of the material keep it at the lower side of the barrel 1 65 but as the barrel revolves the pins 13 car-ried by the barrel are constantly passed through the mass thus thoroughly agitating it. In this connection it will be apparent that immediately in the wake of each pin 13 as it thus passes through the 70 mass will be a space relieved from the pressure of the mass into which space the particles will fall from the surrounding mass and in falling the heavier particles displace the lighter and assume a lower position than the lighter. In addition to this particular action of the pins 13 upon the mass, their passage through the mass stirs and agitates the entire mass thus further assisting in the settling of the heavier particles to the bottom of the mass in the ordinary manner of agitation in all operations of this nature which is so well and generally known as to need no specific description here.

While the mass of material is passing 75 from the chute 27 to the overflow 29, and being agitated, all as above described, the plows 23, revolving with the shaft 4, plow through and turn over and agitate the top 80 portion of the mass keeping it thoroughly mixed and saturated with the water. Also, it will be noted that the top portion of the mass, while being thus agitated, is subjected to the direct action of the spray of 85 water which beats down upon it from the shaft. In this manner the heavier particles are worked and settled and washed out of the upper part of the mass of material into the lower part where they are still further 90 settled to the very bottom of the mass by the agitation of the pins 13 and the revolution of the barrel as above described. It will also be noted that the plows 23 will 95 interrupt the water which would otherwise flow in a stream over the surface of the material and will constantly mix the water with the material thus preventing the carrying off by a stream of water of that part 100 of the gold or other values which is in very fine particles, in which manner much of the values are lost in ordinary operations of 105 this class.

When the heavier particles have been settled to the bottom of the mass, as above 110 described, they naturally tend to follow down the incline to the large end of the barrel but are caught in riffle 11, and, as the barrel revolves in the direction indicated 115 by the arrow, the riffle acts as a worm or screw conveyer and forces the heavy material above it, up the incline until it reaches flange 17 over which it is forced, 120 dropping into the chamber 19. It will be noted that in order that the riffle may force 125 the material over flange 17, the riffle must be higher than the flange otherwise the material would flow down over the riffle instead of up over flange 17. On the other hand 130 the water and lighter material rising to the 135

surface of the mass are carried off over the overflow 29.

The flange 16 prevents the overflow and waste of any of the heavier material which 5 might be forced up along ring 15 by the pressure of the material behind it along the lower side of the barrel.

In the working of ordinary placer material the heavier material which would pass over 10 flange 17 would be principally black sand and gold. As the barrel revolves the points 20 will agitate this mass and the spray from shaft 4 will wash it and the gold, being heavier, will settle down next flange 17 15 while the black sand and water will flow off at the small end of the barrel as at 30.

The flange 18 holds the gold against rising and flowing back over flange 17, which might otherwise result from the pressure of 20 other gold and heavy material behind it along the lower side of the barrel from flange 17 to the overflow 30. The flanges 17 and 18 thus form a pocket in which the gold 25 or other metal to be recovered is finally collected.

What I claim is:

1. A separator body consisting of a conical barrel having its larger end partly closed by a ring standing in a plane at right angles 30 to its axis, and a flange projecting into the barrel from the inner edge of said ring, said barrel having an annular pocket formed at its smaller end by a flange projecting inward from its body and standing in a plane 35 at right angles to its axis, and a secondary flange projecting from the inner edge of the first-named flange obliquely toward the smaller end of the barrel.

2. In a separator, a body consisting of a 40 conical barrel having its larger end partly closed by a ring in a plane at right angles to its axis, and a flange projecting into the barrel from the inner edge of said ring, said barrel having an annular pocket formed at 45 its smaller end by a flange projecting straight inward from its body and standing in a plane at right angles to its axis and a secondary flange projecting from the inner edge of the first-named flange obliquely toward the smaller end of the barrel; combined with a shaft on which said barrel is mounted, a spiral riffle secured to the inner face of the barrel for feeding the heavier 50 material toward the smaller end thereof, means for admitting water for washing the lighter material through the ring at the larger end of the barrel, and agitating devices between the turns of said riffle.

3. In a separator, a body consisting of a conical barrel having its larger end partly closed by a ring standing in a plane at right angles to its axis, and a flange projecting into the barrel from the inner edge of said ring, said barrel having an annular pocket formed at its smaller end by a flange projecting straight inward from its body and standing in a plane at right angles to its axis, and a secondary flange projecting from the inner edge of the first-named flange obliquely toward the smaller end of the barrel; combined with a shaft on which said barrel is mounted, a spiral riffle secured to the inner face of the barrel for feeding the heavier material toward the smaller end thereof, means for admitting water for washing the lighter material through the ring at the larger end of the barrel, strips disposed longitudinally within the body of the barrel between the turns of the riffle, pins in 60 said strips projecting toward said shaft, 65 radial arms adjustably mounted on the latter, and obliquely disposed plows carried by the arms near said ring, the plows standing in position to clear the inner ends of said pins.

4. In a separator of the class described, the combination with a conical barrel having a ring partly closing its larger end and a pocket for the values at its smaller end, a shaft through the axis of said barrel and on which the latter is mounted, and a spiral riffle within the barrel; of strips disposed longitudinally within the body of the barrel between the turns of the riffle, pins in 70 said strips projecting toward said shaft, 75 radial arms adjustably mounted on the latter, and obliquely disposed plows carried by the arms near said ring, the plows standing in position to clear the inner ends of said pins.

5. In a separator of the class described, a 80 conical barrel mounted upon a hollow shaft, spraying means carried by said shaft, a spiral riffle within said barrel, agitating means carried upon the inner face of said barrel, arms disposed in pairs and clamped 85 at their inner ends to said shaft, their bodies being twisted, and a plow carried by the outer ends of each pair of arms and standing 90 between the turns of the riffle.

In testimony whereof I affix my signature 95 in presence of two witnesses.

EDWIN B. GOODWIN.
